(57) **CLAIM**

The ornamental design for a loudspeaker, as shown and described.

DESCRIPTION

FIG. 1 is a left front perspective view of a loudspeaker; FIG. 2 is a left elevation view thereof, the right side not being part of the claimed design;

FIG. 3 is a front elevation view thereof, the rear side not being part of the claimed design; and,

FIG. 4 is a top plan view thereof.

The bottom of the loudspeaker is devoid of ornamentation. The broken lines immediately adjacent the shaded areas represent the bounds of the claimed design while all other broken lines are directed to environment and are for illustration purposes only; the broken lines form no part of the claimed design.

1 Claim, 2 Drawing Sheets
